UNITED STATES PATENT OFFICE.

JULIEN STRANDERS, OF BROOKLYN, NEW YORK, ASSIGNOR TO AMERICAN CHICLE COMPANY, OF NEW YORK, N. Y., A CORPORATION OF NEW JERSEY.

DESIGN FOR A DISPLAY DEVICE.

56,786.

Specification for Design.

Patented Dec. 14, 1920.

Application filed November 9, 1918. Serial No. 261,933. Term of patent 14 years.

To all whom it may concern:

Be it known that I, JULIEN STRANDERS, a subject of the King of Great Britain, residing at 1296 New York avenue, city of Brooklyn, in the county of Kings and State of New York, have invented a new, original, and ornamental Design for Display Devices, of which the following is a specification, reference being had to the accompanying drawing, forming part thereof.

In the drawing Figure 1 is a front perspective view and Fig. 2 a side perspective view of a display device embodying my new design in its preferred form, certain printed matter thereon being omitted for the sake of clearness.

I claim:

The ornamental design for a display device substantially as shown.

JULIEN STRANDERS.
